UNITED STATES PATENT OFFICE

ARTHUR WILLIAM RAMMAGE, OF WANDSWORTH, LONDON, ENGLAND, ASSIGNOR TO
TROUGH DECKING LIMITED, OF LONDON, ENGLAND, A BRITISH COMPANY

METAL DECKING

Original application filed November 2, 1928, Serial No. 316,848, and in Great Britain November 22, 1927.
Divided and this application filed April 20, 1929. Serial No. 356,850.

This invention relates to metal decking, or trough flooring for bridges, piers, warehouses, roofs, subways, tunnels and the like hereinafter referred to as metal decking.

According to the present invention the metal decking comprises a number of trough sections each having oppositely inclined webs terminating at one end of the section in a vertical portion and at the other end in a horizontal portion and right-angled angle pieces secured to the inner side of the vertical portions and to the overhanging portions of contiguous sections.

The construction of the metal decking from the sections preferably proceeds from the upper surface thereof from which point of vantage all riveting, bolting or welding can take place. Under such conditions no under-staging is necessary and tools and construction plant can be carried forward on the upper surface of the decking as construction thereof proceeds, but it will be seen that by turning the decking upside down it can be equally conveniently riveted, bolted or welded from underneath when used for ceilings in tunnels and under conditions which render outside work inconvenient or impossible owing to earth or surrounding materials.

The right-angled angle pieces may be of steel or other metal as also may be any other parts of the decking.

Referring to the accompanying drawings:

Fig. 1 is a diagrammatic view of one construction of trough section of a shape which facilitates convenient packing together of the sections when not connected.

Fig. 2 shows a section having several corrugations and constructed from one plate.

Fig. 3 is an alternative construction of section to that shown in Fig. 1 and is more particularly adapted for heavier constructions of sections, and

Fig. 4 shows reinforcing or strengthening plates attached to a section.

Throughout the views similar parts are marked with corresponding letters of reference.

In medium depth decking as shown in Fig. 1 the section used has a flat bottom or table

a with two sloping webs or sides *b*, a horizontal portion or flat top or table *c*, and a right angled angle piece *f*. Various sections of this construction are adapted to be riveted, bolted or welded together as shown in Fig. 1 by the right angled angle pieces *f* to form a decking and such sections can all be riveted, bolted, or welded from the upper surface of the decking as work proceeds and the sections are placed in position to be riveted, bolted or welded together. Before erection or after being taken apart for transportation the various sections may, by reason of their shape, be easily packed, one within the other, which saves a great amount of space and facilitates transportation. Instead of one section being formed from one plate as shown in Fig. 1, a series of corrugations of a cross sectional configuration having each corrugation somewhat similar to or exactly corresponding with that shown in Fig. 1 can be formed from one plate as shown in Fig. 2, one end *g* of the corrugations being arranged vertically for the reception of a right-angled angle piece *f*, while the other end *h* of the corrugations is left horizontal as shown.

In the sections forming deep decking, which are usually of heavier construction, each section is formed in more than one part. According to Fig. 3, a section of a shape shown in Fig. 1 is formed in two parts the flat bottom or table *a* having two sloping webs or sides *b* but one of these sides is little more than half the length of the other as a joint *d* is formed at the centre or neutral axis *m, n* of the decking and the upper part of the section as shown by the horizontal portion or flat top or table *c* has a depending sloping side or web *e* adapted to be riveted, bolted or welded to the shorter length of side or web *b* at the neutral axis joint *d*. Such parts of sections can as readily be packed together for transportation as the complete sections shown in Fig. 1 and if the two parts forming each section are riveted, bolted or welded together before being placed in position to form the decking all the riveting, bolting or welding for fastening the sections together can be carried out from the upper surface of the decking as the erection thereof proceeds.

This provision of bolting, riveting or welding together of the sections from the upper surface of the decking is rendered practicable by means of the right-angled angle pieces *f* 5 as will be readily understood by referring to any figures of the drawings.

It will be seen that by shaping the trough section substantially as shown, packing facilities are made easy and each section can 10 be formed in two or more parts if desired. Also, a number of sections can be riveted, bolted or welded together at the works or elsewhere before being packed for transportation.

15 Further, for very light decking a number of corrugations could be formed in one plate as previously described and as shown in Fig. 2 of the drawings and yet retain the advantage of being fitted within each other for 20 packing and transporting operations, and, finally, reinforcements of the plates for special purposes can be readily accomplished by the attachment of plates *k* as shown in Fig. 4 of the accompanying drawings.

25 This application is a division of my co-pending application Serial No. 316,848.

What I claim is:—

30 1. A metal decking comprising a number of trough sections each having oppositely inclined webs terminating at one end of the section in a vertical portion and at the other end in a horizontal portion, said horizontal portion overhanging the vertical portion of a contiguous section, and right-angled angle 35 pieces secured to the inner side of the vertical portions and to the overhanging horizontal portions of contiguous sections.

2. A metal decking comprising a number of trough sections each having oppositely inclined webs terminating at one end of the section in a vertical portion and at the other end in a horizontal portion, said horizontal portion overhanging the vertical portion of a contiguous section, and right-angled angle 45 pieces secured to the inner side of the vertical portions and to the overhanging horizontal portions of contiguous sections, said sections being formed in parts secured together at joints lying on the neutral axis.

50 3. A metal trough decking section having oppositely inclined webs one of which terminates in a vertical portion and the other in a horizontal portion of said section, said horizontal portion being of such extent as to overhang the vertical portion of a contiguous section, the said vertical portion being adapted to receive on its inner side a right-angled angle piece for connection with the overhanging horizontal portion of a contiguous section.

4. A metal trough decking section having oppositely inclined webs formed in parts secured together at joints lying on the neutral axis one of which webs terminates in a vertical portion and the other in a horizontal por-

tion of said section, said horizontal portion being of such extent as to overhang the vertical portion of a contiguous section, the said vertical portion being adapted to receive on its inner side a right-angled angle piece for connection with the overhanging horizontal portion of a contiguous section. 70

5. A metal trough decking section having oppositely inclined webs of which one terminates in a vertical portion and the other in a horizontal portion of said section, said horizontal portion being of such an extent as to overhang the vertical portion of a contiguous section, the said vertical portion being provided on its inner side with a right-angled angle 75 piece for connection with the overhanging horizontal portion of a contiguous section. 80

6. A metal trough decking section having oppositely inclined webs, of which one terminates in a vertical portion and the other in a horizontal portion of said section, said last mentioned web being jointed along the neutral axis, said horizontal portion being of such extent as to overhang the vertical portion of a contiguous section, and said vertical 85 portion being adapted to receive on its inner side a right-angled angle piece for connection with the overhanging horizontal portion of a contiguous section. 90

7. A metal decking comprising a number 95 of trough sections each having inclined webs, terminal vertical portions and terminal horizontal portions overhanging terminal vertical portions of contiguous sections in combination with right angled angle pieces secured 100 to the inner side of the vertical portions and to the overhanging horizontal portions.

8. A metal trough decking section according to claim 3 including stiffeners applied to said section. 105

9. A metal decking according to claim 1 including stiffeners applied to said sections.

10. A metal trough decking section according to claim 4 including stiffeners applied to said section at the portion thereof between 110 the inclined webs, and at the said horizontal portion where it adjoins its said web.

In witness whereof I have signed this specification.
